United States Patent Office

Des. 185,894
Patented Aug. 11, 1959

185,894

COMBINED TOOL CASE AND KEY CHAIN

Collins T. Dawson, Shelton, Conn., assignor to The W. E. Bassett Company, Derby, Conn., a corporation of Connecticut

Application March 25, 1957, Serial No. 45,416

Term of patent 14 years

(Cl. D87—3)

FIG. 1.

FIG. 2.

FIG. 3.

FIG. 4.

Fig. 1 is a front view in elevation of the combined tool case and key chain;

Fig. 2 is a view in side elevation of the parts shown in Fig. 1;

Fig. 3 is a rear view in elevation of the parts shown in Fig. 1; and

Fig. 4 is a view similar to Fig. 1, but showing the case in open position.

Tools indicated in the drawing by broken lines are shown for illustrative purposes only.

I claim:

The ornamental design for a combined tool case and key chain, as shown and described.
